UNITED STATES PATENT OFFICE.

GEORGE A. WEHNER, OF SAVANNAH, GEORGIA.

TARGET.

1,093,667.

Specification of Letters Patent. Patented Apr. 21, 1914.

Application filed March 8, 1913. Serial No. 753,137.

To all whom it may concern:

Be it known that I, GEORGE A. WEHNER, a citizen of the United States, residing at Savannah, in the county of Chatham and 5 State of Georgia, have invented certain new and useful Improvements in Targets; and I do declare the following to be a full, clear, and exact description of the invention, such as will enable others skilled in the art to 10 which it appertains to make and use the same.

This invention is a target, and the object of the same is to produce a target forming part of a coin-controlled game apparatus, 15 which target itself is composed of a group or battery of hoods mounted on a pivotal support at one end of a passage which we will call the "gallery," and associated with mechanism for turning the hoods so that 20 their mouths shall be closed to the gallery with the exception of one hood. The mouth of the latter being open causes this hood alone to serve for a time as the target, and before each shot is made the hood last set 25 open and shot at is closed and another one is opened. While the mouth remains open during the time the shot is made and the target may not therefore be called a movable one, it is in effect a changeable target 30 so that it is impossible for a player who has hit the target at one shot to hold the shooter in rigid position and repeat his success. The game or apparatus contemplates the 35 employment of a specific form of shooter whose details of construction form no part of the present invention further than that it is movably mounted within the casing of the apparatus, and a check-controlled mechanism whereby parts are connected by the 40 insertion of a coin so that the player as he loads the shooter must necessarily close the hood last shot at and open another, although he has no choice which hood he will thus 45 expense. While considerable latitude may be allowed the manufacturer as to what shooter, loader, and check-controlled mechanism be employed in the construction of the complete game or apparatus which includes my improved form of target, it will 50 be obvious that the structure is not complete and the game cannot be played without some mechanisms of this character and with which the target is designed to coact.

The invention forming the subject matter

of the present application is more fully described and claimed below, and shown in the accompanying drawings wherein—

Figure 1 is a front elevation of the complete structure embodying my improved target and the shooter which I preferably employ therewith. Figs. 2 and 3 are vertical sections taken respectively on the lines 2—2 and 3—3 of Fig. 5. Fig. 4 is a front elevation similar to Fig. 1 excepting that the face plate and forward portion of the casing has been removed. Fig. 5 is a vertical section, taken on about the line 5—5 of Fig. 3. Figs. 6 and 7 are sectional details of the connector and the loader, showing the parts in different positions. Fig. 8 is an enlarged front elevation of the target alone, and Fig. 9 a similar rear elevation thereof. Figs. 10, 11, and 12 are enlarged sections through the target, taken respectively on about the lines 10—10, 11—11, and 12—12 of Fig. 9. Fig. 13 is a front elevation of the shooter alone.

The shooter S illustrated herewith may be of any suitable form which coacts successfully with the remainder of the mechanism, so long as it is pivoted as at P within the casing and has projecting handles H by which it may be turned on its pivot, and preferably I would provide the shooter with an arrow or index hand A which serves as a sight so that the player may turn the shooter on its pivot to direct this arrow at the open hood of the target in its effort to strike the same. As will be obvious, one of the handles is pivoted, and the structure of the shooter is such that the coin itself serves as the projectile and is shot from the shooter by retracting and then releasing a leaf spring which is actuated by the movable handle. The loading mechanism L for such a shooter would ordinarily be hardly more than an opening or chute into which the coin was deposited and by means of which it was delivered to the shooter S: but, as the hoods of the target are to be set by the act of loading the shooter with a coin, I make use of the loader as part of the setting mechanism.

The coin-controlled mechanism for setting the hood is illustrated herewith as of the connector type whereby the insertion of a coin in the loading mechanism connects a knob- or handle-operated shaft with the set-

ting mechanism proper, so that the subsequent turning of said shaft closes one hood and opens another. As herein illustrated, a coin inserted at the inlet 1 into the chute 1 as seen in Fig. 5 drops against an incline 2 in the wall of said chute and is thereby thrown against the back of a hook 3 which constitutes the connector, the upper end of the shank of this hook being pivoted as at 4 to a swinging member 5 which is in turn pivoted at one end as at 6 and has its other end 7 overlying a cam 8 mounted on a shaft 9 which has a knob or handle 10 on its front end and movable over the front of the main 15 casing 11. The structure of the latter is too well known and of too little importance in the present case to need an elaboration at this point. The lower end of the hook 3 when the same hangs pendent from its pivot 20 4 as seen in Fig. 5, projects through a slot 12 in one wall of the chute 1 opposite its incline 2, and the insertion of a coin 13 as seen in Fig. 6 causes the hook 3 to be swung a little on its pivot so that its bill 14 is engaged beneath a projection 15 on a second swinging member 16 which is pivoted at 17 within the casing 11 and to the rear side of an upright partition 18 therein. This partition divides the entire interior of the casing into an open 30 front space or gallery 19 which is normally clear excepting for the presence of the shooter S therein, and at the lower end of this gallery is a money drawer 20 for receiving the coin, while the target is disposed 35 at the upper end of said gallery and one hood at a time is thrown into communication with it as seen in Fig. 11.

I repeat here that any appropriate form of check-controlling mechanism may be employed instead of that just described and generally lettered C in the drawings, so long as a manually-controlled member 5 is connected by the insertion of a coin with a swinging or movable member 16 which latter in turn actuates the setting mechanism next to be described in detail; and in the present application I make no claim to the specific details of the check-controlled mechanism.

50 The setting mechanism comprises a push rod 21 suitably guided as by slots 22 through its body engaging headed pins or screws 23 in the rear of the partition 18, a suitable pivot 24 at its upper end to which is loosely connected a link 25, a shaft 26 journaled in suitable bearings and extending across the casing, a ratchet wheel 27 fast on one end of the shaft, a pawl 28 engaging this ratchet, and a swinging lever 29 whose inner end 55 is mounted loosely on the shaft, whose body carries said pawl, and whose outer end is pivoted at 29' to the upper end of the link 25. By this or any equivalent form of setting mechanism, the vertical movement of the free end of the swinging member 16 is

transmitted through the push rod 21 and link 25 to the outer end of a lever 29 which in turn, through the pawl-and-ratchet mechanism, sets up an intermittent rotary motion to the shaft 26 that extends across the battery or group of hoods; and as this shaft and the members on it must be specially constructed with reference to the construction of the hoods themselves, they may be said to be part of the target. It is only essential, 75 as far as the setting mechanism is concerned, that the swinging or vertical reciprocating movement of the free end of the member 16 shall be converted into an intermittent rotary movement of the shaft 26 to set the target properly; and, as above explained, said member 16 is moved by the manually controlled member 5 through the connecting mechanism actuated by the insertion of a coin. 80

The target is mounted on a cross partition or shelf 30 which extends across and closes the upper end of the gallery 19, and I may say at this point that any coin which the operator projects upward by means of the shooter S, and that fails to enter the mouth of the open hood, strikes this shelf and falls back through the gallery 19 into the money drawer 20 where it is of course retained within the apparatus for subsequent removal by the owner. On the other hand, any coin which strikes this target, as indicated by the arrow in Fig. 4, is deflected rearward by it through an opening 31 in the partition 18 (see Fig. 11) and directed by a wing on the 95 hood so that it strikes under a lip 32 formed at the upper edge of a transversely inclined runway 33, and drops into the latter and is carried by it, as seen in Fig. 5, to the outlet O where it may be delivered into a premium 100 cup 34 for return to the player as a reward for making a good or successful shot. I may also add that it is quite possible in localities where premiums of this kind are not permitted, to turn the runway 33 downward inside the casing and deliver the coin in the money drawer after all—possibly causing the coin to strike a bell or in some other way indicate a bull's eye during its course 110 from the target to the money drawer. In some localities, furthermore, the law requires 115 that something be given as a consideration for every coin deposited in a machine of this character, whether the marksmanship of the operator is good or bad. In that event it is quite possible to amplify the coin-controlled mechanism by the addition to the apparatus of a vending or delivery mechanism so that packages of some commodity may be delivered to the player at each insertion of a coin, 120 whether he hits the target or not; and such vending apparatus could be controlled or tripped by the coin in its passage through the loading mechanism, so that the commodity 125 would be delivered to the player anyway. 130

The target proper consists of a plurality of hoods 40 carried by said shelf 30, and as they are duplicates of each other I will describe but one. In the drawings I have shown five such hoods, standing on lines converging toward a common center which is the pivot P of the shooter S, and each has its mouth 41 disposed downward within the opening 31 through the partition 18 and preferably provided with side wings 42 so that the mouth is clearly defined and will of course be of a proper size to receive the coin projected by the shooter. The body of the hood 40 is hinged as at 43 to or beneath the shelf 30, and rises past the rear edge of the same in what might be called a tail 44 drawn normally forward by a light spring 45; and said tail carries the wing 46 above referred to which coat with the lip 32 in the runway 33 as best seen in Fig. 11. With this specific structure of the hoods, the setting mechanism will include fingers 47 set in the shaft 26 at angles to each other, as indicated in Fig. 10, each finger by preference moving through a groove or slot 48 in the shelf 30 as said shaft is rotated in the manner described above. It follows from this construction that if the parts are properly proportioned and disposed so that one vertical reciprocation of the push rod 21 turns the shaft 26 for about one-fifth of a complete revolution, this movement will cause the finger 47 which last engaged a hood-tail 44 as seen in Fig. 11, to slip off the same so that the spring 45 restores this hood to closed position as seen in Fig. 12, while another finger moves through its groove 48 and engages the tail of another hood 40, to turn the latter on its hinge 43 and open its mouth (in a manner which will be clear to the reader), all in plain sight of the operator through the glass front of the casing 11. Nor is it necessary that the fingers 47 on the shaft 26 be set in regular succession which would open the mouths of the hoods in regular order; nor is it in fact necessary that the fingers be of the same length which would cause said mouths to open all to the same degree, although this I would prefer in order that each player may have the same chance as his predecessor and his success may depend entirely upon his good marksmanship.

I do not wish to be limited to details of construction, even of the target itself and the setting mechanism therefor. In addition to the suggested change just mentioned, it is quite possible that the mouths 41 of the several hoods could be differently shaped from each other or of different widths transversely of the casing, in addition to or independent of the fact that they might be more or less opened by the length of the fingers; and the manufacturer or proprietor of this apparatus may amplify and complicate its possibilities by the addition of collateral

ideas, such as the painting of the various hoods different colors, the offer of a special prize in case a certain hood is struck repeatedly or successively or under some other conditions, the covering or obscuring of one of the hoods (for instance) by painting or pasting something on the glass front of the casing, and in many other ways not necessary to mention. It is of course possible that the proprietor may remove the shaft 26 and its fingers from time to time, and substitute another shaft wherein the fingers are differently disposed thereon, of different lengths, or some bent and others not. But all these possible amplifications or modifications of the idea need hardly be illustrated and will not be elaborated herein.

I reserve the right to make changes in details as come within the scope of the invention covered by the appended claims, and the proportions, materials, and exact construction of parts may be left to the manufacturer.

The operation of this complete apparatus, including the target, will now be as follows, assuming that the parts stand as seen in Fig. 1 and the casing is provided on its exterior with suitable instructions: A player approaches and inserts a coin—say a penny—at the inlet I, and it travels down the chute 1 and moves a hook 3 from the position shown in Fig. 5 to that shown in Fig. 6, and lodges against the incline 2. He then turns the handle in one direction or the other, and it is quite possible to provide the machine with vending mechanism of the selective type so that if the handle be turned in one direction a certain commodity such as candy is delivered, whereas if the handle be turned in the other direction matches for instance might be delivered to the player. The movement of said handle 10 turns the cam 8 and raises the member 5, the hook or connector thereby raising the member 16 and freeing the coin 18, so that the latter drops through the loader L as seen in Fig. 7, and passes forward completely through the partition 18 as indicated in Fig. 3 and is delivered into the shooter S. Herein, if the shooter be of the construction shown in Fig. 1, it falls into a pocket adjacent the main pivot P and onto a spring as indicated; and the player by grasping the handle H may turn the shooter so that the sight or arrow A is directed at the open hood, when he pinches the handles together, trips the spring, and projects the coin at the target. If he makes a bull's eye, the coin passes into the mouth 41 of the hood and is deflected by the wing 46 thereof so that it is projected beneath the lip 32 and drops into the runway 33, whereby with the construction illustrated in the drawing it is delivered through the outlet O into the premium cup 35 and handed back to the player; and he therefore gets his shot 130

for nothing in any event, and possibly his shot and the merchandise which has been handed him. If he fails to hit the target, the coin strikes the lower side of the shelf 30 and falls through the space or "gallery" 19 into the coin drawer 20 whence it is subsequently removed by the operator. Meanwhile the lifting of the member 16 by the hook or connector has raised the push rod 21 so that, before the player has had time to manipulate and spring the shooter, the setting mechanism has turned the shaft 26, and a cam or finger 47 other than the one which opened the hood as seen in Fig. 1, now comes into action and opens some other hood—the precise one not being known to the player—while the spring 45 closes the first hood which was open when the player inserted his coin. Therefore it will be seen that at the time of inserting a coin the player does not know what his target is to be, nor the size of the mouth if it should happen that the proprietor has inserted a shaft 46 having fingers of different lengths. This provision I consider important, for if it were always one target at which the coin was to be projected, some rascal would mark the casing at a point where the upper handle H should be set to cause the projected coin to accurately strike that target, and thereafter the utility of the apparatus would be destroyed. With the possibilities above suggested, even though five marks were made on the casing, the proprietor can confuse subsequent players who seek to defraud him if he will but substitute another setting shaft with fingers of various lengths and differently disposed than those on the one in question, or possibly he might simply bend the fingers on this shaft or even bend the arrow A. From time to time the coin drawer will be opened and emptied, and if the apparatus be provided with vending mechanism the merchandise channels or magazines must be refilled.

45. What is claimed as new is:

1. The herein described target comprising a group of hoods, and means for opening their mouths successively and irregularly toward the player.
50. 2. The herein described target comprising a group of hoods disposed in a row transverse to the direction in which the player will shoot, and means for opening their mouths one at a time.
55. 3. The herein described target comprising a group of hoods disposed in a row transverse to the direction in which the player will shoot, spring actuated means for closing their mouths, and setting mechanism opposing said means and opening the mouths of the hoods one at a time.
60. 4. The herein described target comprising a group of hoods disposed in a row transverse to the direction in which the player will shoot, a support to which said hoods are

pivoted with their mouths disposed toward the player, springs normally swinging said hoods in a direction to close their mouths, and setting mechanism opposing said means and opening the mouths of the hoods one at 70 a time.

5. The herein described target comprising a group of hoods disposed in a row transverse to the direction in which the player will shoot, a support to which said hoods are 75 hinged on a line struck on a curve around the point whence the projectile will be shot, said hoods having their mouths disposed toward the player, springs normally swinging said hoods in a direction to close 80 their mouths, and setting mechanism opposing said spring and opening the mouths of the hoods.

6. A target consisting of a support disposed transversely to the line in which the projectile will be shot, a row of hoods whereof each has a flat body standing alongside said support and an open mouth disposed toward the point whence the projectile will be shot, springs individually connecting the 90 rear ends of said bodies with said support, loose connections between the mid-length of said bodies and support, a shaft carried by the latter, and fingers thereon variously disposed to contact irregularly with the rear 95 ends of said hoods and move them in opposition to the tension of said springs.

7. A target consisting of a support, a row of hoods whereof each has a flat body standing alongside said support and an open 100 mouth disposed toward the point whence the projectile will be shot, springs individually connecting the rear ends of said bodies with said support, loose connections between the mid-length of said bodies and support, a shaft carried by the latter, fingers thereon variously disposed to contact irregularly with the rear ends of said hoods and move them in opposition to the tension of said 105 spring, a longitudinally movable push rod, 110 a pawl-and-ratchet mechanism on said shaft, and connections between this mechanism and the rod.

8. The combination with a casing containing a gallery, a shelf across the upper 115 end of said gallery and having grooves in its upper face, a shaft mounted on said shelf, a series of irregularly disposed fingers projecting from said shaft and adapted to move through the grooves in the shelf, and means for turning the shaft intermittently; of a series of targets hinged to said shelf and having open mouths at their lower ends and upstanding tails projecting past said shelf and grooves respectively and into the path 120 of said fingers, for the purpose set forth.

9. The combination with an upright casing containing a gallery, a shelf across the upper end of said gallery, a shaft mounted on said shelf, a series of irregularly 130

disposed fingers projecting from said shaft, and means for turning the shaft intermittently; of a series of targets hinged to said shelf and having open mouths at their lower 5 ends and upstanding tails projecting past said shelf and into the path of said fingers, and springs drawing said tails forward and normally opposing the action of said fingers.

10. The combination with an upright casing having a vertical partition producing a gallery forward of it within the casing, the partition having an opening through its upper portion, a shelf across the upper end of said gallery above the opening in the partition, a shaft mounted on said shelf, a series of irregularly disposed fingers projecting from said shaft, and means for turning the shaft intermittently; of a series of targets hinged to said shelf and whose bodies move 15 through said opening and have open mouths at their lower ends adapted to be exposed within the gallery forward of said partition, upstanding tails at their upper ends projecting into the path of said fingers for the 20 purpose set forth, and springs drawing said tails forward and normally opposing the 25 action of said fingers.

11. The combination with an upright casing having a vertical partition producing a gallery forward of it within the casing, the partition having an opening through its upper portion, a transversely inclined runway within the casing in rear of said partition and beneath the opening in the latter, 30 the runway having a lip across its upper edge, a shelf across the upper end of said gallery above the opening in the partition, a shaft mounted on said shelf, a series of irregularly disposed fingers projecting from 35 said shaft, and means for turning the shaft intermittently; of a series of targets hinged to said shelf and whose bodies move through said opening and have mouths at their lower 40 ends adapted to be exposed within the gallery forward of said partition, tails at their upper ends, wings projecting rearwardly and upwardly from the hood-bodies and co-acting with said lip on the runway for the 45 purpose set forth, and springs drawing said tails forward and normally opposing the action of said fingers.

12. The combination with an upright casing having a transverse partition and a transparent front, producing a gallery between said front and partition, the latter having an opening at its upper end, a shelf across the interior of the casing above said opening, a transversely inclined runway within the casing in rear of and beneath said 55 opening and having a forwardly projecting lip across its upper edge, and a premium cup to which said runway delivers; of a series of hoods movably connected with said shelf and having open mouths at their lower 60 ends adapted to be exposed when said ends 65

are swung forward through the opening in said partition, a wing projecting upward and rearward from each hood and adapted to coact with said lip for the purpose set forth, and setting mechanism carried by the 70 shelf for swinging said hoods irregularly into open position one at a time.

13. The combination with an upright casing having a transverse partition and a transparent front producing a gallery between said front and partition, the latter having an opening at its upper end, a shelf across the interior of the casing above said opening, a transversely inclined runway within the casing in rear of and beneath said opening, and a premium cup to which said runway delivers; of a series of hoods movably connected with said shelf and having open mouths at their lower ends adapted to be exposed when said ends are swung forward through the opening in said partition, means for swinging all said hoods to the rear so as to normally house them in the space behind the gallery and close their mouths, setting mechanism in the casing above said 80 shelf and adapted to act on the hoods irregularly and one at a time to overcome said means, and devices for actuating said setting mechanism.

14. The combination with an upright casing having a transverse partition and a transparent front producing a gallery between said front and partition, the latter having an opening at its upper end, a shelf across the interior of the casing above said opening, a transversely inclined runway within the casing in rear of and beneath said opening, and a premium cup to which said runway delivers; of a series of hoods movably connected with said shelf and having open mouths at their lower ends adapted to be exposed when said ends are swung forward through the opening in said partition, means for swinging all said hoods to the rear so as to normally house them in the 90 space behind the gallery and close their mouths, setting mechanism in the casing above said shelf and adapted to act on the hoods irregularly and one at a time to overcome said means, a vertically movable push 95 rod disposed within the casing and connected with said setting mechanism, a shaft having a handle at the exterior of the casing, and connections between said shaft and push rod.

15. The combination with an upright casing having a transverse partition and a transparent front producing a gallery between said front and partition, the latter having an opening at its upper end, a shelf across the interior of the casing above said opening, a transversely inclined runway within the casing in rear of and beneath said opening, and a premium cup to which said runway delivers; of a series of hoods movably connected with said shelf and hav- 125 130

- ing open mouths at their lower ends adapted to be exposed when said ends are swung forward through the opening in said partition, means for swinging all said hoods to the rear so as to normally house them in the space behind the gallery and close their mouths, setting mechanism in the casing above said shelf and adapted to act on the hoods irregularly and one at a time to over-
10 come said means, a vertically movable push rod disposed within the casing and connected with said setting mechanism, a shaft having a handle at the exterior of the casing and a cam on its interior, a member actuated by the rotation of said cam, a second member pivoted at one end within the casing and connected at its other end with said push rod, and connections between said members.
15 16. The combination with a target comprising a row of hoods, means for normally closing their mouths, and means for opening the mouths irregularly one at a time; of a shooter movably supported remote from said target, and manually controllable means for adjusting the position of the shooter.
20 17. The combination with a shooter pivoted on a support, and manually controllable means for turning it on its pivot and firing it; of a target consisting of a series of hoods mounted on a line curved around said support as a center, means for normally closing their mouths, and means for opening their mouths one at a time.
25 18. The combination with a shooter pivoted on a support, and manually controllable means for turning it on its pivot and firing it; of a target disposed above the shooter and consisting of a series of hoods mounted on a line curved around said support as a center, means for normally closing their mouths, setting means for opening said mouths one at a time, means for loading said shooter, and connections between the loading and setting means, for the purpose set forth.
30 19. The combination with a shooter pivoted on a support, and manually controllable means for turning it on its pivot and firing it; of a target disposed above the shooter and consisting of a series of hoods mounted on a line curved around said support as a center, means for normally closing their mouths, setting means for opening said mouths one at a time, loading mechanism for said shooter, manually operated means for actuating said setting mechanism, and connections between said last means and setting mechanism controlled by said loading mechanism.
35 20. The combination with a shooter pivoted on a support, and manually controllable means for turning it on its pivot and firing it; of a target disposed above the shooter and consisting of a series of hoods having downwardly opening mouths, means for normally closing their mouths, setting mechanism for opening said mouths one at a time, loading mechanism for said shooter, manually operated means for actuating said setting mechanism, and a hook on said last means thrown into connection with said setting mechanism by the insertion of a coin through said loader.
40 21. The combination with a casing having an upright gallery, a target at the upper end thereof comprising a series of hoods having downwardly opening mouths, means for normally throwing said mouths out of the line of the gallery, and setting mechanism for turning the hoods to open their mouths one at a time; of a shooter movably mounted in the lower portion of said gallery, and a loading mechanism consisting of a coin slot whose inlet end opens through the casing in rear of said gallery and whose outlet end is directed into said shooter.
45 22. The combination with a casing having an upright gallery, a target at the upper end thereof comprising a series of hoods having downwardly opening mouths, means for normally throwing said mouths out of the line of the gallery, and setting mechanism for turning the hoods to open their mouths one at a time; of a shooter movably mounted in the lower portion of said gallery, a loading mechanism consisting of a coin slot whose inlet end opens through the casing in rear of said gallery and whose outlet end is directed into said shooter, its body between said ends having an incline at one point and a slot opposite thereto, a manually operable member within the casing, a second member movably mounted within the casing and connected with the setting mechanism, and a connector between said members hanging normally within said slot and actuated by the insertion of a coin.
50 23. The combination with a casing having an upright gallery, a target at the upper end thereof comprising a series of hoods having downwardly opening mouths, means for normally throwing said mouths out of the line of the gallery, and setting mechanism for turning the hoods to open their mouths one at a time; of a shooter mounted movably in the lower portion of said gallery, a loading mechanism consisting of a coin slot whose inlet end opens through the casing in rear of said gallery and whose outlet end is directed into said shooter, its body between said ends having an incline at one point and a slot opposite thereto, a manually operable member within the casing, a second member pivoted at one end in the casing and connected at its other end with said setting mechanism, a projection on the last-named member, and a connector consisting of a hook pivoted at its upper

end to said manually operated member with its body hanging normally in said slot and its bill adapted to be projected into engagement with said projection by the insertion of a coin.

24. The combination with an upright casing having a gallery, a shelf across the interior of the casing, and a transversely inclined runway within the casing in rear of said gallery; of a series of hoods movably connected with said shelf and having open mouths at their lower ends adapted to be exposed when said ends are swung forward, means for swinging all said hoods to the rear behind the gallery and close their mouths, setting mechanism adapted to act on the hoods irregularly and one at a time to overcome said means, a push rod connected with said setting mechanism, a shaft having a handle at the exterior of the casing and a cam on its interior, a member actuated by the rotation of said cam, a second member connected with said push rod, and coin controlled means for connecting said members.

25. The herein described target having a series of openings, members hingedly mounted therein and by which they are normally closed to a missile, and means for

swinging said members to expose said openings one at a time.

26. The herein described target having a series of openings, hoods hingedly mounted therein and by which they are normally closed to a missile, and means for moving the hoods to expose their mouths one at a time for the reception of said missile.

27. The combination with a target having a series of openings arranged in an arc, and means for exposing them one at a time to a missile; of a receptacle in rear of all said openings for receiving a missile and which passes through any one of them and a shooter pivoted at the center of said arc.

28. The combination with a target having a line of openings, and means for exposing them one at a time in irregular order along the line; of a receptacle in rear of the target along said line for receiving the missiles which pass through said openings.

In testimony whereof I have hereunto set my hand in presence of two subscribing witnesses.

GEORGE A. WEHNER.
